MAXIMILIAN J. ORAFSIK, OF CHICAGO, ILLINOIS

ICE SKATE

Application filed November 26, 1928. Serial No. 321,959.

The present invention relates to ice skates and has reference more particularly to an improved runner construction.

One of the important objects of the present invention is to provide skates wherein an ice engaging or gliding strip is detachably secured on the bottom of the runner so that when the strip becomes dull, the same may be removed and replaced with a duplicate strip 10 that has previously been sharpened, thus providing a means whereby the ice skates will at all times have a sharp skating edge.

Another important object is to provide an ice skate of the above mentioned character 15 wherein the bottom of the runner and the removable strip are cooperatively associated together to permit the proper fitting of the strip on the bottom edge of the runner.

Still a further object is to provide an ice 20 skate of the above mentioned character which is simple in construction, inexpensive, strong and durable and further well adapted to the purpose for which it is designed.

Other objects of the invention will become 25 apparent as the nature of the invention proceeds and when taken in connection with the accompanying drawing.

In the accompanying drawing, forming a 30 part of this application, and wherein like reference characters designate like parts throughout the several views:

Figure 1 is a side elevation of an ice skate 35 of a conventional construction, showing the improved runner associated therewith.

Figure 2 is an elevational view of the removable strip per se.

Figure 3 is a vertical sectional view, taken approximately upon the line 3—3 of Figure 40 1, and

Figures 4, 5, and 6 are similar sections showing modifications of the adjacent faces of the runner and removable strips.

In the drawings, with reference more particularly to Figures 1, 2, and 3, the numeral 1 designates generally an ice skate that includes a runner 2 from which extends upwardly the vertical stay members 3 to support the sole plate 4 and the heel plate 5, in the conventional manner.

The bottom edge of the runner 2 is formed

at spaced intervals with threaded sockets 6 for a purpose to be presently described.

The invention comprehends the provision of a removable strip for the bottom of the runner, and the strip 7 may be constructed of the same material as the runner or of dissimilar material, if so desired. The strip 7 is provided at spaced intervals with openings which register with the sockets 6 to accommodate the screws 8 that are threaded into the socket, the heads of the screws being confined within the channel shaped strips to prevent said screws from coming in contact with the ice.

When the parts are secured together in the manner shown in Figure 3, the strip 7 will be rigidly secured to the bottom edge of the runner 2 and the lower edges of the sides of the channel shaped strip are sharpened so as to permit the skates to readily and easily glide over the ice. When the runner 7 becomes worn or the edges thereof become dull, the same may be removed by pulling the screws 8 and replaced with a duplicate strip that has been previously sharpened.

In Figures 4, 5, and 6 of the drawings, I have shown modifications of the shape of the adjacent faces of the runner and the removable strip, and it is to be understood that each of the runners shown in the modifications is formed with openings to accommodate the securing screws and at the lower ends of the openings are countersunk so that the heads of the screws will not project beyond the ice engaging face of the strip.

It will thus be seen from the foregoing description that I have provided an improved ice skate that will enable a sharp ice engaging strip to be used at all times, and this without the necessity of having to lose much time or labor in attaching or removing the strip from the runner. Also the dull strip may be sharpened either while attached to the runner or removed therefrom as may be desired.

While I have shown the preferred embodiment of my invention, it is to be understood that various changes in the size, shape and arrangement of parts may be resorted to, without departing from the spirit of the in-

vention or the scope of the appended claim.

I claim:

5 In a skate, a runner formed with a longitudinally extending groove in the bottom face thereof and further having longitudinally spaced threaded sockets in the groove, an ice-engaging strip fitting against the bottom face of the runner, a longitudinally extending rib on the strip for disposition in the groove of the runner, said strip being provided with vertical openings for registering with the threaded sockets, and securing screws extending through the openings in the strip and threaded into the respective 10 sockets to rigidly secure the strip on the runner, the side faces of the strip forming a continuation of the respective side faces of the runners.

15 In testimony whereof I affix my signature.

20 MAXIMILIAN J. ORAFSIK.
